UNITED STATES PATENT OFFICE.

FRANK E. LONAS, OF NEW YORK, N. Y.

INTERNAL-COMBUSTION ENGINE.

1,163,934.

Specification of Letters Patent. Patented Dec. 14, 1915.

Application filed March 24, 1914. Serial No. 826,891.

To all whom it may concern:

Be it known that I, FRANK E. LONAS, a citizen of the United States, and residing at New York, in the county of New York and State of New York, have invented certain new and useful Improvements in Internal-Combustion Engines, of which the following is a specification, such as will enable those skilled in the art to which it applies to make and use the same.

This invention relates to internal combustion engines, in which the cylinders are provided with heads containing explosion chambers, and in which the inlets and exhausts to and from the explosion chambers are controlled by valves placed in valve spaces or chambers surrounded or inclosed partially or wholly by water passages or chambers forming part of a water circulating system in which the water preferably flows in a continuous direction; and the object of the invention is to provide improved means for operating the valves by which the inlet and exhaust to and from the explosion chambers in the heads of the cylinders are controlled, and in which the means for operating said valves are located in the top portion of the engine above the cylinders and the heads thereof, and in direct connection with said valves, and also in operative connection with the main crank shaft of the engine.

Another object is to so locate the mechanism that it may be easily inspected and readily assembled and dis-assembled without disturbance of the crank case, the cylinders, the pistons or the valves themselves.

In the case of a motor employing several cylinders; the water chambers or passages are preferably in communication with a suitable source of supply at or near the lower ends of the cylinders, and the cylinders and their heads are inclosed in jackets forming part of the water circulating system, and said chambers or passages are in communication at or near the lower ends of the cylinders with a water supply pipe, and at their upper ends or above the explosion heads of the cylinders with a common collector or source of discharge, of such character that the chambers or passages of the water circulating system are disposed in parallel lines or columns between the inlet and the outlet or discharge, whereby there is a continuous flow of the cooling medium in one direction from the point of entree to the point of discharge, and by reason of this construction, a

more effective and practical cooling of those parts of the engine which are apt to become overheated is provided for.

The invention is fully disclosed in the following specification, of which the accompanying drawing forms a part, in which the separate parts of my improvement are designated by suitable reference characters in each of the views, and in which:

Figure 1 is a vertical section through one of the cylinders of the engine, its extension head and corresponding parts, and;—Fig. 2 a sectional plan view taken in two different horizontal planes, the left hand portion of said figure being approximately a section on the line 2—2 of Fig. 1, and the right hand portion of said figure being approximately a section on the line 2^a—2^a of Fig. 1.

In the accompanying drawing, two cylinders and corresponding parts are shown, but it will be understood that any desired number of cylinders may be employed, and in the practice of my invention, I provide cylinders *a* having explosion heads *b* which consist of extensions of said cylinders, and with which the manifold passages *c* communicate, and the cylinders *a* are inclosed by a jacket or casing *d* having an enlarged head portion *d*² which incloses the explosion heads *b* of the cylinders *a*, and the manifold passages *c* and the heads *b*, the manifold passages *c* and the jacket or casing *d*—*d*² are also preferably formed integrally, but said parts are provided with a detachable cap or cover *e* forming in connection therewith an enlarged head portion and a chamber *e*² in which the valve operating mechanism is placed, as hereinafter described and the bottom of which is formed by a horizontal partition *e*³ formed in and constituting part of the enlarged head portion *d*² of the jacket or casing *d* and through which the tops of the explosion heads *b* of the cylinders *a* pass.

The explosion heads *b* of the cylinders *a* are provided in their outer walls with annular valve chambers *f* which open upwardly into the chamber *e*² and in which are placed cylindrical or sleeve valves *g* which are vertically movable in the construction shown, and which are provided with ports or passages *g*² and *g*³ which control the inlet and exhaust ports or passages *c*² and *c*³ between the manifold passages *c* and the explosion chambers in the heads *b* of the cylinders *a*.

The jacket or casing *d*—*d*² forms in connection with the cylinders *a*, their heads *b*

and the manifold passages c , water chambers or passages h around the cylinders a , and h^2 around the manifold passages c , and the other water chambers or passages h^3 are formed in the explosion heads b of the cylinders a , and in the tops of the heads b are water chambers h^4 with which the water chambers or passages h^2 , h^3 and h communicate, and the chambers or passages h^3 in the explosion heads b of the cylinders a communicate with the chambers or passages h below the valve chambers f , as shown at h^5 , and tubular water passages h^6 are arranged between the cylinder heads and communicate with the chambers or passages h^2 and with a water chamber or passage h^7 in the top of the cap or cover e , and the central tubular water passages h^8 provide a communication with the water chambers or passages h^4 in the top of the explosion heads of the engines and with the water chamber or passage h^7 in the top of the cap or cover e , said central tubular water passages h^8 being provided in the top portion thereof with ports h^9 and being also closed, in the construction shown, by screw threaded caps h^{10} .

The tubular passages h^6 are preferably composed of two parts one of which is connected with the removable cap or cover e and the other with the horizontal partition e^3 , said parts being connected in the plane that separates the removable cap or cover e from the part d^2 of the jacket or casing d , and this connection may be made in any desired manner.

With this construction, the water enters through the jacket or casing d into the water passages or chambers h through suitable supply pipes in the usual manner, these supply pipes and their inlets being not shown, and said water passes upwardly through the chambers or passages h , h^2 , h^3 , h^4 , h^6 and h^8 into the water chamber or passages h^7 from which it is discharged in the usual manner, and it will thus be seen that there is a continuous flow of the cooling water in one direction, and without interruption, from the time it enters the water chambers or passages h till it is discharged through or by the water chamber or passage h^7 , this flow of the water being indicated by the arrow x , and in this continuous flow of the water, the body thereof is divided into separate columns or branches which flow inwardly through and longitudinally of the heads b of the cylinders a and parallel with the outer and inner walls of the valve chambers f in which the valves g are placed, and the columns of water which flow through the chambers or passages h^3 in the heads b of the cylinders a not only serve to cool the explosion chambers in said heads, but also to cool the inner walls of the valve chambers, while the columns of water which flow through the chambers or passages h^2 serve

to cool both the outer walls of said chambers and the manifold passages c .

The valve chambers f are provided with inner linings f^2 and outer linings f^3 between which linings the valves g are movable, and these linings facilitate the construction or formation of said valve chambers and cheapen said construction, as said linings may be much more easily machined and finished than could the walls of said valve chambers.

The outer linings f^3 of the valve chambers are provided with upwardly directed extensions f^4 having, in the form of construction shown, annular shoulders f^5 which rest on the outer walls of the valve chambers which are extended above the partition plate e^3 of the enlarged top portion d^2 of the jacket or casing d , and the upwardly directed extensions f^4 of the outer linings of the valve chambers form sleeve guides in which the sleeve valves are movable.

The cylindrical valves extend above the explosion heads b of the cylinders and are provided in their opposite sides with vertical openings g^5 the side walls of which are thickened, as shown in Fig. 2, and at right angles to the openings g^5 in the top portions of the valves g are sleeve bearings g^6 .

The chambers e^2 , or the walls thereof formed by the parts d^2 and e are provided with strengthening web members i and suitable bearings o arranged longitudinally of the engine and on the opposite sides of the heads of the cylinders, and in which are mounted parallel crank shafts o^2 and p^2 provided respectively with pinions or gears o^3 and p^3 which mesh with a helical gear y mounted on a shaft y^2 which extends downwardly and is geared in connection with the main crank shaft of the engine in any suitable way, said connection and the main crank shaft being not shown, and the pinions or gears o^3 and p^3 are of such comparative dimensions that the shaft o^2 turns at half the speed of the motor, while the shaft p^2 turns at the same speed as the motor.

Loosely mounted on the cranks o^1 and p^1 of the shafts o^2 and p^2 are box bearings r in which are slidably mounted transverse or cross beams or yokes q having central circular hub members q^2 which enter the tops of the sleeve valves g , and the opposite sides of which are provided with bearing studs q^3 which fit in the sleeve bearings g^6 of the said valves. The circular hub members q^2 of the transverse or cross beams or yokes q are of less dimensions than the interior dimensions of the sleeve valves g , and the central tubes h^8 of the water circulating system pass upwardly through these hub members, and are also of less dimensions than the interior apertures or passages therethrough.

With this construction, the movement of

the sleeve valves corresponds exactly with the vertical movement of the center of the cross beams or yokes q , and the movement of the sleeve valves is a composite movement having for result the effect of opening and closing of the inlet and exhaust ports of the explosion heads of the cylinders at the required moments, for permitting a four cycle motor to accomplish its cycle.

10 In the accompanying drawing, the end portions of the transverse or cross beams or yokes q are shown larger than those portions of said beams adjacent to the central hubs q^2 thereof, but this feature of the construction is immaterial and is occasioned by the method of constructing said beams, the end portions thereof preferably consisting of tubes into which the parts thereof adjacent to the central hub members are inserted 15 and secured by welding, brazing or otherwise.

From the foregoing description, it will also be seen that the valves g do not extend down to the cylinders proper, but do extend 20 above the explosion heads of said cylinders, as do also the linings f^2 and f^3 of the valve chambers f and the outer linings f^3 of said valve chambers also extend above the cross beams q of the valve operating apparatus 25 and above the crank shafts o^2-p^2 as do also the valves g , said valves and the upward extensions f^4 of the outer linings f^3 of the valve chambers being provided in their opposite sides with vertical slots or openings 30 through which the beams q pass, and in which said beams operate.

The crank shafts which control the movements of the cross beams q may be operated otherwise if desired, than by the vertical shaft y^2 , and my invention is not limited to an engine placed in a vertical position; nor to an engine involving cylindrical or sleeve valves, nor to any specific system of water circulation, or means for circulating water 40 in connection with the cylinders, their explosion heads, or the valve chambers, nor is the said invention limited to any specific form of explosion heads for said cylinders, nor to any specific position of the valves 45 with reference to the cylinders, and changes in and modifications of the form of the valves and the location thereof, together with other features of construction herein shown and described may be made, within 50 the scope of the appended claims, without departing from the spirit of my invention or sacrificing its advantages.

Having fully described my invention, what I claim as new and desire to secure by 55 Letters Patent is:—

1. An internal combustion engine having a ported cylinder, a slide valve controlling the ports thereof, and means for operating said valve consisting of two oppositely disposed crank shafts located in the top portion

of the engine and operatively connected to the valve, one of the crank shafts rotating at a greater speed than the other.

2. An internal combustion engine having a ported cylinder, a slide valve controlling the ports thereof, and means for operating said valve consisting of two oppositely disposed crank shafts, a cross beam pivotally connected to the valve and operatively connected to both crank shafts, one of the crank shafts rotating at a greater speed than the other.

3. An internal combustion engine having a ported cylinder, a slide valve controlling the ports thereof, and means for operating said valve consisting of two oppositely disposed crank shafts in the top portion of the engine, a cross beam connected to the valve and operatively connected to both crank shafts, one of the crank shafts rotating at 85 engine speed and the other at one-half engine speed.

4. An internal combustion engine having a cylinder with a ported combustion head provided with a sleeve valve adapted to control the ports thereof, and means for operating said valve consisting of two oppositely disposed crank shafts in the top portion of the engine, and a cross beam pivotally connected with the valve and operatively connected to both crank shafts, one of the crank shafts rotating at engine speed 90 and the other at one-half engine speed.

5. An internal combustion engine having cylinders with ported combustion heads provided with sleeve valves adapted to control the ports thereof, and means for operating said valves consisting of two oppositely disposed crank shafts in the top portion of the engine, a cross beam directly connected to each of the valves and operatively connected to both crank shafts, one of the crank shafts rotating at engine speed and the other rotating at half engine speed.

6. An internal combustion engine having a ported cylinder, a sleeve valve encompassing the combustion space, and means for operating said valve consisting of two oppositely disposed crank shafts in the top portion of the engine and operatively connected to the valve, one of said shafts rotating at a greater speed than the other.

7. A combustion engine comprising cylinders provided with combustion chambers inclosed by slide valve chambers in which are mounted slide valves which control the ports of the cylinders, and means for operating said valves consisting of cross yokes pivotally connected to said valves, and parallel crank shafts, oppositely disposed and fitted with loosely mounted bearings through which the ends of the cross yokes are movable.

8. An internal combustion engine having a plurality of cylinders provided with com-

4

bustion heads, inlet and exhaust manifolds communicating therewith by means of the usual ports or passages, and sleeve valves adapted to control said ports or passages, 5 said cylinder and explosion heads being provided with a water jacket or casing forming water passages and having an enlarged head portion provided with a removable cap forming part of said head 10 portion, and forming in connection therewith a top chamber independent of the water circulating passages, and means for operating said valves consisting of two parallel crank shafts placed in the opposite 15 sides of said chamber and cross beams in operative connection with said valves and said crank shafts.

9. An internal combustion engine having a plurality of cylinders provided with combustion heads, inlet and exhaust manifolds communicating therewith by means of the usual ports or passages, and sleeve valves adapted to control said ports or passages, 20 said cylinders and explosion heads being provided with a water jacket or casing forming water passages and having an enlarged head portion provided with a removable cap forming part of said head portion, and forming in connection therewith a top chamber 25 independent of the water circulating passages, and means for operating said valves consisting of two parallel crank shafts placed in the opposite sides of said chamber and cross beams in operative connection with 30 said valves and said crank shafts, one of said crank shafts being adapted to rotate at engine speed and the other at half engine speed.

10. An internal combustion engine having a ported cylinder, a slide valve controlling the ports thereof, and means for operating said valve consisting of two oppositely disposed crank shafts, a cross beam directly connected with the valve and operatively 40 connected with both crank shafts, one of the said crank shafts being rotatable at a greater speed than the other.

11. An internal combustion engine provided with a sleeve valve and means for 45 operating said valve consisting of oppositely disposed crank shafts, a cross beam

operatively connected with the valve and slidably and rotatably connected with both crank shafts, one of the crank shafts being rotatable at greater speed than the other. 55

12. An internal combustion engine having a ported cylinder, a slide valve controlling the ports thereof, and means for operating said valve consisting of two oppositely disposed and parallel crank shafts, 60 a cross beam directly and operatively connected with the valve and operatively connected with both crank shafts, one of said crank shafts being rotatable at a greater speed than the other. 65

13. An internal combustion engine having a ported cylinder, a slide valve controlling the ports thereof, means for operating said valve, consisting of two crankshafts mounted in the top portion of the engine, 70 fitted with loosely mounted bearings in which is carried a cross yoke free to slide in said bearings, said cross yoke being pivotally connected to the valve and one of said shafts rotating at a greater speed than the 75 other.

14. An internal combustion engine having a ported cylinder, a slide valve which controls the intake to and exhaust from said cylinder, and means located in the top portion of the engine for operating said valve, consisting of a cross yoke pivotally connected to the valve and operatively connected to two crank shafts fitted with loosely mounted bearings through which the 80 cross yoke is slidable. 85

15. An internal combustion engine having a ported cylinder, a slide valve, and means for operating said valve, consisting of a plurality of crank shafts mounted in 90 the top portion of the engine and operatively connected to the valve, one of said shafts rotating at a higher speed than another.

In testimony that I claim the foregoing 95 as my invention I have signed my name in presence of the subscribing witnesses this 23rd day of March 1914.

FRANK E. LONAS.
